HEINRICH RASMUSSEN, OF LUND, SWEDEN

LIQUID-LEVEL INDICATOR.

SPECIFICATION forming part of Letters Patent No. 628,353, dated July 4, 1899.
Application filed November 18, 1898; Serial No. 696,815. (No model.)

To all whom it may concern:

Be it known that I, HEINRICH RASMUSSEN, of Lund, Sweden, have invented certain new and useful Improvements in Devices for Holding or Supporting Gages Indicating the Level of a Liquid in a Recipient, of which the following is a specification.

The object of the present invention is a device for holding or supporting gages or similar tubes, indicating at the outside of a recipient the level of the liquid inside same.

The invention is illustrated in the accompanying drawing, showing a longitudinal section of the device.

15 The holder or support consists of two pieces of metal *a* and *b*, arranged each at one end of the open gage-tube *c*. The pieces *a* and *b* are connected by means of a rod *d* going through the tube *c*, the lower end of this rod being firmly attached to or screwed into the said piece *a*, while the other extremity is threaded and provided with a nut *g*. In the piece *a* is further arranged a groove for receiving a ring of india-rubber or other suitable packing material, against which the lower extremity of the tube may be pressed, and thus form a tight joint.

By means of a passage *l* in the piece *a* communication is established between the interior 30 of the recipient and the lower end of the gage-tube. The piece *b* at the upper end of the tube *c* is provided with a collar, between which and the upper extremity of the tube is inserted a packing-ring *f* of suitable material.

35 The piece *b* is bored right through lengthwise, and its upper edge rests against the nut *g*, screwed onto the extremity of the rod *d*. Between the collar and the upper edge of the piece *b* is a hole *h* through the wall of the piece *b*. The upper end of the tube *c*, together with the piece *b*, project into a metal tube *h* of a suitable inside diameter, the upper end of this tube being closed by means of a screw-cap *m*. The tube *h* is in firm connection with the upper part of the recipient, and communication is established between the interior of the recipient and the interior of the tube *h* by means of an opening *i*. It will thus be seen that communication is existing between the upper and lower part of the recipient.

If the nut *g* after the screw-cap *m* having

been removed is turned, the piece *b* will move toward the piece *a* and the packing-rings *e* and *f* be compressed. While, as already pointed out, the packing-ring *e* will make a tight joint between the lower extremity of the tube *c* and the piece *a*, the packing-ring *f* will not only make a tight joint between the upper extremity of the tube *c* and the piece *b*, but also between the piece *b* and the tube *h*, as the ring *f* when it is pressed in between the tube and the collar will expand in the direction of the diameter.

The tube *c* may either be placed outside the recipient altogether, but it is preferable to place it into a suitable recess arranged in the recipient in order to prevent breakage. The tube *c* may be provided with a scale for reading off direct how many pints or pounds of liquid the recipient is containing.

The above-described device for holding the gage-tube has that great advantage over those hitherto employed that the tube proper in no places is lying up against metal surfaces, which circumstance will permit of the upper and lower support being able to move somewhat in relation to each other without any danger being incurred of breaking the tube. Furthermore, the tightening of the joints may be effected very easily and simply by turning the nut *g*.

Having now particularly described and ascertained the nature of this said invention and in what manner the same is to be performed, I declare that what I claim is—

1. A gage, comprising top and bottom supports formed with seats, one of the supports being tubular, a glass tube between the supports, a rod secured to one of the supports and extending through the glass tube and tubular support and having its end threaded, and a nut on the threaded end of the said rod and resting upon the tubular support, substantially as described.

2. A gage-tube, comprising a bottom support having an annular groove in its upper face and provided with a passage leading out through it, a packing in the groove, a glass tube having its lower end resting upon the packing, a tubular top support having one end projecting into the glass tube and provided with an exterior collar, a packing between the collar and the upper end of the

glass tube, a rod secured to the bottom support and extending up through the glass tube and the top support, and a nut on the upper end of the rod, said nut resting upon the upper end of the top support, substantially as described.

3. A gage-tube, comprising a bottom support having an annular groove in its upper face and provided with a passage leading out through it, a packing in the groove, a glass tube having its lower end resting upon the packing, a tubular top support having one end projecting into the glass tube and provided with an exterior collar and an opening above the collar, a packing between the collar and the upper end of the glass tube, a rod

secured to the bottom support and extending up through the glass tube and the top support, a nut on the upper end of the rod and resting upon the end of the top support, and a tube fitting over the upper end of the glass tube and the top support and provided with a lateral opening and a cap, substantially as described.

In testimony that I claim the foregoing as my invention I have signed my name in presence of two subscribing witnesses.

HEINRICH RASMUSSEN.
